(57) **CLAIM**

The ornamental design for a combined container with push-and-slide locking mechanism, as shown and described.

DESCRIPTION

FIG. 1 is a top, front, right-side perspective view of a combined container with push-and-slide locking mechanism, in a closed configuration, showing the new design; FIG. 2 is a top, front, left-side perspective view of the combined container with push-and-slide locking mechanism, in the closed configuration;

FIG. 3 is a bottom, front, right-side perspective view of the combined container with push-and-slide locking mechanism, in the closed configuration;

FIG. 4 is a bottom, front, left-side perspective view of the combined container with push-and-slide locking mechanism, in the closed configuration;

FIG. 5 is a bottom, back, right-side perspective view of the combined container with push-and-slide locking mechanism, in the closed configuration;

FIG. 6 is a bottom, back, left-side perspective view of the combined container with push-and-slide locking mechanism, in the closed configuration;

FIG. 7 is a bottom, right-side perspective view of the combined container with push-and-slide locking mechanism, in the closed configuration;

FIG. 8 is another bottom, left-side perspective view of the combined container with push-and-slide locking mechanism, in the closed configuration;

FIG. 9 is a front elevation view of the combined container with push-and-slide locking mechanism, in the closed configuration;

FIG. 10 is a back elevation view of the combined container with push-and-slide locking mechanism, in the closed configuration;

FIG. 11 is a right-side view of the combined container with push-and-slide locking mechanism, in the closed configuration;

FIG. 12 is a left-side view of the combined container with push-and-slide locking mechanism, in the closed configuration;

FIG. 13 is a top view of the combined container with push-and-slide locking mechanism, in the closed configuration;

FIG. 14 is a bottom view of the combined container with push-and-slide locking mechanism, in the closed configuration;

FIG. 15 is a top, front, right-side perspective view of the combined container with push-and-slide locking mechanism, with a primary lid in an opened configuration;

FIG. 16 is a top, front, left-side perspective view of the combined container with push-and-slide locking mechanism, with the primary lid in the opened configuration;

FIG. 17 is a top, back, right-side perspective view of the combined container with push-and-slide locking mechanism, with the primary lid in the opened configuration;

FIG. 18 is a top, back, left-side perspective view of the combined container with push-and-slide locking mechanism, with the primary lid in the opened configuration;

FIG. 58 is a left-side view of the combined container with push-and-slide locking mechanism, with the primary lid and the secondary lid in the respective opened configurations; FIG. 59 is a top view of the combined container with push-and-slide locking mechanism, with the primary lid and the secondary lid in the respective opened configurations; and, FIG. 60 is a bottom view of the combined container with push-and-slide locking mechanism, with the primary lid and the secondary lid in the respective opened configurations.
